UNITED STATES PATENT OFFICE.

WILLIAM HENRY HAVEN, JR., OF OXFORD, ASSIGNOR OF ONE-HALF TO JOHN RITCHIE, OF BROOKLINE, MASSACHUSETTS.

CHANNELING-MACHINE.

SPECIFICATION forming part of Letters Patent No. 398,155, dated February 19, 1889.

Application filed July 31, 1888. Serial No. 281,606. (No model.)

To all whom it may concern:

Be it known that I, WILLIAM HENRY HAVEN, Jr., a citizen of the United States, residing at Oxford, in the county of Worcester and State 5 of Massachusetts, have invented new and useful Improvements in Channeling-Machines; and I do hereby declare that the following, taken in connection with the accompanying drawings, is a specification.

10 My invention relates to improvements in the construction and means of operating that class of machines generally known as the "McKay Channeling-Machines," and the objects of my invention are, first, to enable the operator to keep the sole, as it is propelled and moved by the feed-wheel and the presser-wheel and as it is guided and turned by the operator's hands, in a horizontal plane, and, second, in a mechanism to facilitate the 15 driving and operating the machine by motive power. I attain these objects by the mechanism illustrated in the accompanying drawings, in which—

Figure 1 is a vertical section of the machine, omitting parts of the mechanism not required to be shown for a clear defining of my invention. Fig. 2 is a front elevation of upper part, Fig. 1. Fig. 3 is a top view of the plane-table, the dotted lines showing the position of its supporting-brackets beneath; Fig. 4, a front view of the plane-table; Fig. 5, a cross-section through the lines $x-x$ of Fig. 3; Fig. 6, a side view of the treadle; Fig. 7, a cross-section through the lines $z-z$ of Fig. 1. 30 Similar letters refer to similar parts throughout the several views.

A denotes the frame; B, the toothed feed-wheel; C, its shaft; D, a geared wheel fixed to the shaft, which engages with the geared 40 wheel E, which revolves on a pin, a , attached to the frame; F, the presser-wheel attached to the shaft b , supported by the lever G. A geared wheel, d , is attached to the shaft C, engaging with a geared wheel, e , and communicates motion to the presser-wheel; H, the edge-wheel, or guide-roll. The arrangements of these parts, as also of the cutters, (not shown in the drawings,) are the same as in the McKay machine, and are old and in 45 use. The part to which my improvement re-

lates in this portion of the machine is the addition and adaptation of a plane-table, I, which I attach to the frame A by means of the brackets j , in position that its upper surface is in the plane of the upper edge of 55 the feed-wheel and extending in front of it, and surrounding the edge-wheel.

In operating the machine the sole is laid upon the plane-table, and as it is carried between the feed-wheels and the presser-wheel 60 and against the edge-wheel, guided by the hands of the operator, it is retained by the plane-table in the requisite horizontal plane. Any deviation from the horizontal of the sole as it is carried against the cutting-knife and 65 grooving-tool causes inequalities in the channel and groove cut.*

To the geared wheel E, I attach a belt-pulley, J, (in the place of the crank usually used).

g denotes a revolving shaft, to which is attached a hub, K, having a conical surface, l .

N denotes a hub movable on the shaft, having a conical surface, l' , fitting to the conical surface l , and a belt-pulley, L. The pulleys J and L are connected by a belt, r . By means 75 of a bent lever, m , which is moved by a treadle, n , the operator can force the conical surface l' against the conical surface l , producing the friction required to give motion to the pulley L and by a belt to the pulley J. 80

It is important that the channel be commenced and ended at certain points on the sole, and that while a groove is also cut, it shall begin after and end before the channel; and to enable the operator to effect these 85 results, and to perform the work expeditiously, he must have the means to start and to stop the motion of the wheels suddenly.

It will be apparent that the operator, by a slight movement of the treadle, can quickly 90 set the machine in motion and almost instantly stop it, and that it will be entirely under his control.

I am aware that prior to my invention a patent was granted to Wells & Bray, March 95 11, 1856, No. 14,426, for a shoe-sole machine which has a metal carriage whose outline is similar to the sole of a shoe, having geared teeth cut in its circumference which engage with a pinion by which it is rotated upon a 100

table. The sole is attached to this carriage and is carried under cutting-tools. This arrangement differs entirely in form, use, and position from my plane-table. The feed-wheel, presser-wheel, and edge-wheel of the McKay machine, which are parts of the combination of my claims, are not in the shoe-sole machine.

I am also aware that prior to my invention the arrangement of frictional cones operated by a treadle has been used for other purposes.

What I claim as my invention, and desire to secure by Letters Patent, is—

1. In a channeling-machine, the combina-

tion of a feed-wheel, B, a presser-wheel, F, and an edge-wheel, H, with a plane-table, I, substantially as described.

2. The combination, in a channeling-machine, of a feed-wheel, B, a presser-wheel, F, an edge-wheel, H, with the hub K, having a conical surface, l , and the hub N, with a conical surface, l' , for the purpose and substantially as set forth.

WILLIAM HENRY HAVEN, JR.
